UNITED STATES PATENT OFFICE.

FRANK H. FRISSELL, OF MIDDLETON, CONNECTICUT, ASSIGNOR TO THE RUSSELL MANUFACTURING COMPANY, OF MIDDLETON, CONNECTICUT, A CORPORATION OF CONNECTICUT.

THREAD-WINDING LOOM.

SPECIFICATION forming part of Letters Patent No. 721,792, dated March 3, 1903.

Application filed September 20, 1900. Serial No. 30,598. (No model.)

To all whom it may concern:

Be it known that I, FRANK H. FRISSELL, a citizen of the United States of America, residing and having post-office address at Middletown, in the county of Middlesex and State of Connecticut, have invented a certain new and useful Improvement in Thread-Winding Looms, of which the following is a description, reference being had to the accompanying drawings, wherein—

Figure 1 is a diagrammatic plan view of parts of a loom bearing said improvement. Fig. 2 is an elevation view of parts of a loom bearing said improvement, the view being from side A, Fig. 1. Fig. 3 is a view on an enlarged scale of a revolving spool-carrier. Fig. 4 is a view in central longitudinal section of the spool-carrier shown in Fig. 3.

The object of the improvement is an attachment for a weaving-loom designed and adapted to wind and coat a warp-thread with another thread as and before it is woven into the textile fabric produced by the loom.

In the weaving of suspenders having elastic quality for trousers and the like it is customary to weave in with the warp threads of india-rubber, more or less in number. The two threads of rubber which are nearest the edge of the suspender are liable to be unduly rubbed and abraded by the action of the reed.

One purpose for which this improvement may be used is to wind those outer rubber threads with another thread of any suitable material — cotton or linen, for instance — which shall protect those rubber threads from the abrading action of the reed.

It is a matter of course that the improvement may be applied to the winding of as many threads as may be desired, which threads may be of any suitable material. The improvement, however, will be herein described as applied to the winding of the outer rubber threads of suspenders.

In the accompanying drawings the letter *a* denotes parts of the frame of a loom.

b denotes the lay, carrying the weft-shuttles *c*.

d denotes a sword-arm, to which the lay is attached.

e denotes a connecting-rod or pitman. 50

f denotes the crank which gives the lay its vibrating motion.

g denotes ordinary cotton warp-threads, and

h denotes parts of the harness.

The rubber threads which are to be incorporated in the suspender are massed in lengths upon the roll *i*. Tension is given to these rubber threads as they are woven into the fabric by means of the weight *k* and the band *k'*, from which it is pendent, bearing on the 60 surface of the rubber threads which are wound upon the roll *i*. The rubber threads (one of them is lettered *l*) proceed from the roll *i* down underneath the roll *m*, thence to be woven into the fabric along with the other 65 warp-threads.

The letter *n* denotes a centrally-open revolving spool-carrier. It bears, hung therein pivotally, the spool of thread *o*. It is the thread from that spool which is wound around 70 the rubber thread *l*, the necessary retarding tension being given by the spring *p*. The revolving spool-carrier *n* is borne by and upon the hollow shaft *r* and receives its rotary motion therefrom. The rubber thread *l* passes 75 through this hollow shaft and out at the end of the carrier *n*. As the carrier *n* revolves it winds and coats the rubber thread with the thread of cotton or the like which proceeds from the spool *o*, and the rubber thread thus 80 coated is duly woven into the textile fabric as the operations of the loom proceed. The rotation of the shaft *r* is given by the rotating shaft *t* through the medium of the bevelled pinions *s*. 85

It is to be noted that the rubber thread and the thread from the spool *o* are not twisted or wound about one another, but that the rubber thread is straight and the coating-thread is wound spirally about it. 90

The coating of but one of the rubber threads has been described; but it will be readily understood that others may be thus coated in number as desired.

I claim as my improvement—

1. The combination with the mechanism of a weaving-loom adapted for the manufacture of textile fabrics, of means for forming a cov-

covering on one or more of the warp-threads while they are being incorporated in said fabric. 2. The combination with the mechanism of a weaving-loom adapted for the manufacture of textile fabrics, of automatically-operated means for spirally winding one or more of the warp-threads of said fabric with a covering material while said threads are being incorporated in the fabric. 3. The combination with a weaving-loom, of a centrally-open winding device revolvably mounted in connection therewith, and adapted to form a covering on the warp-threads before they are incorporated into the fabric. 4. The combination with a weaving-loom, of a centrally-open winding device revolvably

mounted in connection therewith, and a spool of covering material carried thereby, said material being adapted to be spirally wound about said warp-threads before they are incorporated into the fabric, substantially as described.

5. The combination with the mechanism of a weaving-loom adapted for the manufacture of textile fabric, of means for forming a covering on the outside warp-threads of said fabric while they are being incorporated therein, substantially as described.

FRANK H. FRISSELL.
